UNITED STATES PATENT OFFICE.

WILLIAM JACOB KUNTZ, OF YORK, PENNSYLVANIA, ASSIGNOR TO McGANN MANUFACTURING COMPANY, INCORPORATED, OF YORK, PENNSYLVANIA, A CORPORATION OF PENNSYLVANIA.

ROTARY DRIER.

Application filed March 6, 1923. Serial No. 623,273.

To all whom it may concern:

Be it known that I, WILLIAM J. KUNTZ, a citizen of the United States, and resident of York, in the county of York and State 5 of Pennsylvania, have invented certain new and useful Improvements in Rotary Driers, of which the following is a specification.

My invention relates generally to driers, more particularly to improvements in driers 10 of that type including rotating drying shells, a stationary feed head and sealing means arranged between the rotating drying shells and stationary feed head, and it consists in the combinations, constructions and 15 arrangements herein described and claimed.

An object of the invention is to provide in a drier of the type described an improved sealing arrangement between the rotating drying shells and stationary feed head, 20 which sealing arrangement is adapted to permit limited expansion and contraction of the relatively moving adjacent parts of the drying shells and feed head without impairing 25 the efficiency of the drier.

A further object of the invention is to provide in a drier of the character described 30 a sealing arrangement which is effective to satisfactorily close and seal the space between the feed head and one end of the rotating drying shells without there being any necessity of machining the relatively moving 35 adjacent parts of the drier in order to insure a serviceable fit of such relatively moving parts with one another.

A still further object of the invention is to provide in a drier of the character described 40 a sealing arrangement between the rotating drying shells and feed head which is adapted to prevent escape of heated gases from the drier shells between the drying 45 shells and feed head without causing any friction between the relatively moving parts of the drier.

A still further object of the invention is 50 to provide in a drier of the character described a sealing arrangement which is extremely simple in construction, applicable to driers varying considerably in the details of construction, and economical to manufacture and thoroughly practical commercially.

Other objects and advantages will be apparent from the following description, considered in conjunction with the accompany-

ing drawings, forming a part of this application, in which—

Figure 1 is a view showing in side elevation a drier equipped with my improved sealing arrangement, portions of the shells of the drier being broken away and other 60 portions being shown in section,

Figure 2 is a relatively enlarged view, mainly in longitudinal vertical section and partly in side elevation of the feed head, sealing arrangement and fragmentary portions of the parts of the drier exhibited in Figure 1 which are associated with the feed head and sealing arrangement,

Figure 3 is a fragmentary sectional view showing my improved sealing arrangement 70 interposed between adjacent parts of the outer drying shell and feed head of the drier exhibited in the preceding views, and

Figure 4 is a section along the line 4—4 of Figure 3.

It is necessary in driers employing rotating connected together inner and outer or concentric drying shells and a stationary feed head in communication with the space between the drying shells to provide means 80 for sealing the space between the rotating outer drying shell and the adjacent end of the feed head so that the heated gases conducted into the inner drying shell may be drawn through the inner shell to the remote 85 end of the latter and then rearwardly between the outer drying shell and the inner drying shell to a draft creating means, such as an exhaust fan. Sealing means provided in double-shell driers prior to my invention, 90 of which I am aware, are in general unsatisfactory in that a relatively great amount of machining of the relatively moving parts of the sealing means is necessary in order to provide a sealing arrangement of the types 95 employed prior to my invention which will prevent escape of gases between the adjacent ends of the feed head and outer drying shell. Considerable friction results from the operation of such prior sealing means 100 and moreover, sealing arrangements for driers of the character described provided prior to my invention and of which I am aware are extremely cumbersome and heavy.

As will be understood from the following, a sealing arrangement embodying the present invention and embodied in a drier of the type described affords facilities for

attaining the hereinbefore recited objects of the invention and for overcoming the hereinbefore described objectionable features of other sealing arrangements with which similar drier constructions are equipped.

Referring now to the drawings, I show in Figure 1 a drier including concentric inner and outer drying shells 1 and 2 held in spaced connected together relation by 10 any suitable known means (none being shown) and being supported for rotation.

In the embodiment of the invention illustrated, tires 3 encircle the outer shell 2 and are secured to the latter. These tires 15 rest upon bearing wheels 4, each of which is rotatably supported upon a base 5. The outer shell 2 also is provided with a concentric ring gear 6 in mesh with the drive gear or pinion 7 which may be driven from 20 a motor 8 or other prime mover.

A substantially drum-shaped feed head 9 is associated with the flue 10 of a suitable furnace 11 and is disposed at one end of the drying unit which comprises the connected together shells 1 and 2. The feed head 9 is shown as resting upon cast iron supports 12 which surmount a base 13.

The feed head 9 is substantially annular in form and includes an inner cylindrical wall or ring 14 which is considerably larger diametrically than the furnace flue 10 and through which the latter extends, the outer end of the flue 10 or in other words the end of the flue 10 remote from the furnace terminating within the outer shell 2 at a considerable distance from the adjacent end of the feed head 9 and short of the plane of the adjacent end of the inner shell 1. As stated, the cylindrical inner wall 14 of the feed head is considerably larger diametrically than the furnace flue 10 and an annular space is thus provided between the feed head cylinder 14 and the portion of the furnace flue extending through the feed head. A cylindrical baffle or deflector ring 15 is supported at one end in an outwardly offset or enlarged end portion 16 of the inner drying shell 1 and extends through the feed head cylinder 14 in spaced concentric relation to the latter and also in spaced encircling relation to the furnace flue 10. The cylindrical baffle 15 closely interfits the enlarged end portion 16 of the inner drying shell 1 at one end and terminates at its other or free end substantially in the plane of the end of the feed head proximate to the furnace. The cylindrical baffle 15 is provided for a purpose to be hereinafter described.

The feed head 9 also includes a pair of 60 edgewise disposed or vertical end plates 17 and 18 respectively which are mounted upon the inner cylinder 14 of the feed head and are secured upon the latter and held in spaced parallel relation by any suitable 65 known fastening means. An outer ring

member 19 included in the feed head is supported at one end upon an inwardly extending flange 20 at the outer edge of the plate 18 and is secured at its other end to the end plate 17 through the agency of 70 a binding ring 21 or like securing means. The feed head ends 17 and 18 are substantially circular in configuration but are extended radially at the upper sides of the feed head and together with the outer ring 75 19 are formed at the upper side of the feed head to define a connection 22 adapted for connection with one end of the intake tube 23 leading to the casing 24 of an exhaust fan which is shown as being mounted upon 80 the furnace 11, the exhaust fan being shown as having an outlet or discharge tube 25 which may lead to any desirable place. With the arrangement described, a substantially annular space is defined within the 85 feed head by the inner cylindrical ring 14, the end plates 17 and 18 and the outer ring 19. An inclined feed chute 26 extends through a suitable opening in the end plate 17 in fluid tight contact or fit with the latter 90 and through the annular space within the feed head at one side of the inner ring 14 and terminates at its lower end in register with an opening 27 formed through the end plate 18, the walls of the feed chute being 95 secured at the lower end of the latter to the walls of the opening 27 so that the feed chute is out of communication with the annular space within the feed head. The opening 27 preferably does not extend above 100 the horizontal plane of the axis of the ring 14. A door or valve shown diagrammatically and indicated at 28 may be provided for controlling the flow of materials through the feed chute 26.

The construction described so far may vary considerably in details from that described since this construction forms no part of my invention except in so far as it operates with the parts which will now be 110 described. The parts which will now be described comprise a sealing mechanism arranged between the end plate 18 of the feed head 9 and the adjacent end of the outer shell 2. Such sealing mechanism includes 115 an inner sealing or supporting ring 29 arranged in concentric relation to the cylindrical baffle 15 and having an outwardly extending annular attaching flange 29' disposed flatwise against the outer face of the 120 end plate 18 and firmly secured to the latter in any suitable known manner, as by welding.

With this arrangement, the ring 29—29' is angular in cross sectional contour and extends in spaced concentric relation to the cylindrical baffle 15 beyond the plane of the adjacent end of the outer drying shell 2. A pair of annular disks 30—30 fitting snugly upon the horizontal flange of the inner seal- 130

ing ring 29 are held in spaced parallel relation to each other through the agency of bolts 31 extending through aligned openings in the disk, spacing washers or thimbles 32 disposed on the bolts between the disks and nuts 33 screwed on the bolts until the disks are clamped against the ends of the spacing washers or thimbles. An outer sealing ring 34 closely interfitting and permanently 5 cured to the extreme end portion of the outer shell 2 has an integral inwardly extending flange 35 extending between the spaced apart disks 30—30 and terminating out of contact with the spacing thimbles 32. 10 Disks 30—30 are free to move along the inner sealing ring 29 in order to provide for expansion and contraction.

From the foregoing description of the various parts of the device, the operation 20 thereof may be readily understood. An opening 36 is formed through the upper part of the end plate 18 and establishes communication between the interior of the ring 29 and an annular space within the feed head. 25 The space between the inner sealing ring 29 and the baffle 15 is in open communication with the annular space between the inner and outer drying shells 1 and 2 respectively. This annular space between the inner sealing ring 29 and the cylindrical baffle 15 is 30 of relatively great radial extent. The operation of the exhaust fan will thus cause a suction within the inner sealing ring 29 and within the annular space between the inner and outer drying shells which will result in 35 the heated gases from the furnace flue 10 traversing the inner drying shell 1 for the entire length of the latter, the path of the heated gases being as indicated by the arrows in Figure 1 and extending rearwardly 40 from the end of the inner drying shell remote from the furnace through the space between the inner and outer drying shells and thence through the opening 36 to the 45 take pipe of the exhaust fan. The cylindrical baffle 15 serves to prevent heated gases from the furnace flue from passing directly from the outer end of the latter to the opening 36 instead of traversing the tortuous 50 path indicated by the arrows in Fig. 1. The sealing means hereinbefore described and arranged between the end plate 18 and the outer shell 2 prevent escape of the heated 55 gases from the space between the inner and outer drying shells and the end of the outer shell proximate to the furnace and cooperates with the cylindrical baffle 15 to cause a suction on the inner and outer drying shells when the exhaust fan is operated. 60 Since the inwardly extending flange 35 of the outer sealing ring extends between the axially movable connected together pair of sealing disks 30—30 on the inner sealing ring 29, it will be manifest that neither of 65 the disks 30—30 is positively held in fric-

tional contact with the relatively moving flange 35 and that therefore no appreciable friction results from the operation of the sealing means and consequently no extra burden is placed upon the driving means 70 for the drying shell. Moreover, the relatively moving parts of the sealing means are not likely to be worn out quickly in service. It will be obvious that the relatively moving parts of the sealing arrangement and consequently the relatively moving parts of the drying shell and feed head may expand or contract within certain limits without in any way impairing the efficiency of the sealing means or interfering 75 with the operation of the drier as a whole. The outer sealing ring 34 may be reinforced by spaced integral radial web portions 37 connecting it at intervals with the inwardly extending flange 35. 80

I claim:—

1. In a device of the character described, the combination with a rotating shell and a stationary wall positioned adjacent to one end of the shell, of a ring carried by the wall and extending into the rotating shell in spaced concentric relation to the latter, an inwardly extending annular member carried by the shell in spaced concentric relation to the first ring, and imperforate annular members disposed on the first ring and extending at opposite sides of the inwardly extending annular member beyond the inner edge of the latter. 90

2. In a drier, the combination with rotatably supported connected together concentric drying shells and a stationary feed head positioned adjacent to said drying shells at one end of the latter, said feed head having an end wall proximate to the drying shells and lying in a plane transverse to the axial line of rotation of the shells, said end wall having an opening in line with the space between said shells, of a ring attached to the end wall outwardly of the opening in the end wall and extending into the outer drying shell in concentric spaced relation to the latter, a second ring interfitting the adjacent end of the outer shell, said second ring having an inwardly extending annular flange, and a pair of disks on the first ring and respectively extending outwardly beyond the inner edge of the flange on the second ring at opposite sides of the latter. 105

3. In a drier, the combination with rotatably supported connected together concentric drying shells and a stationary feed head positioned adjacent to said drying shells at one end of the latter, said feed head having an end wall proximate to the drying shells and lying in a plane transverse to the axial line of rotation of the shells, said end wall having an opening in line with the space between said shells, of a ring attached to the end wall outwardly of the opening in the end wall 110

and extending into the outer drying shell in concentric spaced relation to the latter, a second ring interfitting the adjacent end of the outer shell, said second ring having an inwardly extending annular flange, a pair of disks slidable on the first ring and respectively extending outwardly beyond the inner edge of the flange on the second ring at opposite sides of the latter, and means holding 10 said disks in spaced apart parallel relation.

4. In a drier, a sealing device comprising an inner ring having an attaching flange at one end thereof, an outer ring of greater diameter than the first ring and having an inwardly extending annular flange at one end, the inner diameter of said flange being greater than the diameter of said first ring, and a pair of disks slidable on said first ring, the outer diameter of each of said disks being greater than the inner diameter of the flange on the second ring, and means connecting 15 said disks at intervals for holding them in spaced parallel relation in respect to each other.

5. In a drier, a sealing device comprising

an inner ring having an attaching flange at one end thereof, an outer ring of greater diameter than the first ring and having an inwardly extending annular flange at one end, the inner diameter of said flange being greater than the diameter of said first ring, and a pair of disks slidable on said first ring, the outer diameter of each of said disks being greater than the inner diameter of the flange on the second ring, and means connecting 20 said disks at intervals for holding them in spaced parallel relation in respect to each other.

6. The combination with two concentric spaced apart annular members of a pair of connected together sealing disks disposed on the inner annular member in close sliding engagement with the peripheral wall of the latter, and a co-operative annular sealing member carried by the outer annular member and extending inwardly from the latter between 25 said first named sealing disks.

WILLIAM JACOB KUNTZ.
